CHARLES L. BOWDEN, OF CHICAGO, ILLINOIS.

TWO-CYCLE ENGINE.

1,341,838.

Specification of Letters Patent. Patented June 1, 1920.

Application filed May 28, 1917. Serial No. 171,378.

To all whom it may concern:

Be it known that I, CHARLES L. BOWDEN, a citizen of the United States, residing at Chicago, in the county of Cook and State 5 of Illinois, have invented a certain new and useful Improvement in Two-Cycle Engines, of which the following is a specification.

My invention relates to an improved two-cycle engine for use with gas or gaseous mixture which is burned in the engine cylinder and it is a purpose of my invention to overcome by my construction many of the difficulties which have heretofore been experienced in operating engines of this kind.

In connection with two-cycle engines, that is to say in which there is a power stroke for each revolution of the crank shaft with a single acting engine, satisfactory results have been secured for conditions where the engine can run under considerable load. The engine has the advantage over the four cycle type of requiring but one-half the number of cylinders for the same power impulses in a given time and the construction 20 is simpler in that the intake and exhaust ports may be controlled directly by the engine piston instead of requiring valves and valve-operating gearing to control the intake and exhaust as is necessary in connection with the four-cycle type of engine. It has been found, however, under certain conditions of operation that many difficulties arise in operating a two cycle engine, among which may be mentioned, first, that the engine will not run smoothly on a nearly closed condition of the throttle valve on account of the frequent "missing" which occurs, that is to say failure to fire the charge for each rotation of the crank shaft 25 for each cylinder; second, considerable vibration of the engine when running idle which results from the occasional firing of a relatively heavy charge; third, when running idle or with a nearly closed throttle the engine does not appear to scavenge properly; fourth, back-firing takes place frequently when the engine is running with a nearly closed throttle, as a result of which the explosion in the engine cylinder is communicated to the crank case or other compression chamber in which the mixture is initially compressed before being admitted to the engine cylinder; and, fifth, the engine appears to load up with mixture to such an extent that it is difficult to start it. All of 55 these difficulties and others I find to be due to the fact that during the condition of idle running of the engine, that is to say running with a nearly closed throttle in the intake pipe, the engine cylinder receives a relatively small amount of explosive mixture, which, notwithstanding the fact that it is richer than is the case when running on full load owing to the usual construction and operation of the carburetor, is not sufficient to be fired for each working stroke of the piston. This, I find, is not due to the fact that a charge is not admitted to the cylinder for each stroke, but rather to the fact that the charge admitted to the cylinder 60 is so small for idle running that it frequently fails to reach the location of the spark plug and therefore is not in communication with the spark plug when the spark is formed and cannot be fired by the spark. 65 When this is the case the engine "misses" and continues to miss until by successive strokes a sufficient charge is accumulated in the cylinder to reach the spark plug at the time of firing, for which condition an abnormally powerful explosion occurs which results in an extreme shock to the whole structure, producing vibration and noise. This condition is the more pronounced in view of there being practically no load on 70 the engine when for example it is used as the power plant of an automobile and is running with the clutch out, since the engine at this time is not required to drive gearing of any kind, the only load being that represented by the friction of the crank shaft 75 bearings and the parts directly connecting the crank shaft with the piston. It is believed by many that the engine "misses" because it does not scavenge properly and 80 that therefore the gases of combustion of a preceding explosion prevent the next charge being properly fired. This I find to be the case only because of the small quantity of fresh charge admitted to the cylinder when 85 the engine is running with a nearly closed throttle valve.

In my invention I provide an auxiliary firing chamber supplied with mixture for each stroke of the engine through a by-pass 105 connecting with the intake port as a result of which, when the piston of the engine is in a position opening the intake port, an

auxiliary valve mechanism at the same time establishes communication between the said by-pass and the auxiliary firing chamber. The valve mechanism of the auxiliary chamber is preferably of the piston type and operates synchronously with the main piston of the engine, or nearly so, as a result of which the charge is compressed in the auxiliary chamber at the same time that compression occurs in the cylinder and the charge is fired in the auxiliary chamber at or near the condition of maximum compression for which most efficient operation of the engine is secured. In the construction shown in the drawings, the piston valve referred to for the auxiliary chamber is embodied in a construction which in effect is an auxiliary engine piston, the auxiliary chamber being an auxiliary cylinder, the auxiliary piston being provided with a connecting rod, crank and crank shaft geared to the main crank shaft in a ratio of 1 to 1. The volume of the auxiliary cylinder, which is connected at its head end by a suitable port with the head end of the main cylinder, is such that when the engine is operating under no load and with a nearly closed throttle valve, the auxiliary cylinder is completely filled with fresh explosive mixture from the compression chamber for each stroke of the piston and as a result an explosion in the auxiliary cylinder is produced for each stroke of the engine since the spark plug is located in the head end of the auxiliary cylinder or immediately adjacent thereto. The firing which takes place in the auxiliary cylinder communicates through the port referred to at its head end to the charge which is at the same time compressed in the main cylinder and the result is that for all conditions of operation an explosion or firing occurs in the engine for each working stroke of its pistons and therefore for each rotation of the crank shaft. This entirely eliminates the difficulty of vibration when running under no load because the "missing" of the engine is eliminated and, since the engine operates smoothly and quietly for the nearly closed throttle condition, there is no tendency for the operator to change the carburetor adjustment which in the past has frequently been done in a vain attempt to make the engine operate properly under no load. Much of the difficulty in the past has resulted from improper adjustment of the carburetor in attempting to make the engine operate under a no-load condition and an improper adjustment of the timing apparatus, as for example back firing which has been due largely to using a "late" spark, which tendency is entirely eliminated by my construction since the engine works properly under no load with a proper timing of the spark.

65 By my invention I provide a further

means for preventing back firing and for increasing the efficient operation of the engine under no load which consists in providing a divided intake port controlled by a valve operated synchronously with the throttle valve so that, when the throttle valve is nearly closed, the intake port in effect is of much reduced cross section which results in maintaining the velocity of the flow of the fresh mixture through the intake port for a closely throttled condition, this velocity of flow being sufficient to prevent the occurrence of backfiring. With a properly timed spark, however, there is little tendency for backfiring since the explosive mixture has sufficient time interval to be wholly consumed before the intake port is opened by the engine piston.

It will be understood that the pressure exerted upon the auxiliary piston by the firing in the auxiliary cylinder is not lost since the two pistons are connected together as referred to above and, therefore, the auxiliary piston although of small diameter is also a power piston. By my invention I also provide means to retain fresh mixture flowing into the bypass connecting with the auxiliary cylinder so that back flow of the mixture is prevented in said bypass.

My invention will best be understood by reference to the accompanying drawings showing a preferred embodiment thereof, in which—

Figure 1 shows one cylinder of an engine in vertical central sectional view, part of the construction being shown in perspective to facilitate indicating the connections of the controlling valve, the portion of this figure to the right of the center line of the engine and above the broken line being taken along 105 the line 1-1 in Fig. 4 while the remaining section is taken along the line 1-1 in Fig. 4,

Fig. 2 shows in a view similar to Fig. 1 an enlarged sectional view of the intake port and its controlling valve, this figure being 110 taken along the line of 2-2 in Fig. 3,

Fig. 3 is a sectional view of the parts shown in Fig. 2 taken along the line 3-3,

Fig. 4 is a plan view of a four cylinder engine constructed in accordance with my 115 invention, and

Fig. 5 is a view similar to Fig. 1 showing a two-diameter piston type of engine instead of the crank case compression type shown in Fig. 1.

Similar numerals refer to similar parts throughout the several views.

As shown in Fig. 1, the engine consists of a power cylinder 10 in which a power piston 11 is disposed, said piston being connected by a connecting rod 12 with a crank 13 secured to a crank shaft 14 mounted in suitable bearings 15 secured in the crank case 16. The cylinder is provided with an intake port 17 and an exhaust port 18 formed 130

through the side walls thereof near the crank end of the cylinder so that said ports are uncovered by the piston when in its outermost position as is common in two-cycle engine practice. The exhaust port 18 is shown connected with an exhaust manifold 19. The engine shown in Fig. 1 is of the crank case compression type and is provided with a passageway 20 leading from the crank case to the intake port 17. The explosive mixture is introduced into the crank case in a manner to be described by the suction of the piston 11 and the cycle of operation of the engine is similar to that of the ordinary two-cycle engine to the extent that for each rotation of the shaft 14 a charge of explosive mixture is drawn into the crank case and at the same time a charge already communicated to the power cylinder is compressed, and during the reverse stroke of the working piston firing of the compressed charge in the cylinder takes place after which near the end of the stroke the exhaust port 18 first opens relieving the pressure on the gases of combustion in the cylinder, immediately after which the intake port 17 opens permitting the mixture in the crank case compressed by the stroke of the piston under consideration to flow through the passageway 20 and the intake port into the cylinder to scavenge the engine and place a fresh working charge in the cylinder.

The intake port 17 is of novel construction as shown more clearly in Figs. 2 and 3 in that it is divided by a plurality of plates 21 into several ports, said plates extending entirely across the intake port and being conformed to constitute a portion of the inner cylindrical surface of the cylinder. The portion of the intake port 17 opening into the passageway 20 is engaged by a controlling valve 22 rigidly secured to a shaft 23 extending through the casing of the engine and having upon its outer end and rigidly secured thereto an operating crank 24. The valve 22 by the engagement of its cylindrical surface with a corresponding cylindrical bore across the outer end of the intake port 17 controls the amount of opening of the intake port and as a result of the separating partitions 21 when the port is open but a small amount the effective cross section of the intake port is the area between the lowermost plates 21 and the bottom wall of the intake port and in this manner for low pressures of gas in the crank case, as for example when the throttle valve of the engine is nearly closed, a relatively high velocity of flow of mixture through the intake port is maintained. For conditions of running where the throttle valve is opened further the valve 22 is in a position opening more of the intake port thus allowing the mixture which at this time has a greater pressure in the crank case to flow somewhat more freely

through the intake port, the purpose of the construction being to maintain practically uniform velocity of the mixture through the intake port for different operating positions of valve 22. As indicated diagrammatically in Fig. 1, the end of the crank 24 is pivotally connected with an operating rod 25 which also pivotally engages one end of a crank 26 secured to the throttle spindle 27, as a result of which when the rod 25 is operated to move the throttle valve 28 from its nearly closed position shown in Fig. 1 to a wider open position the valve 22 is rotated to open the intake port 17 a corresponding amount, this being continued until when the throttle is wide open the intake port is fully open. The plates 21 are preferably of thin sheet metal and to properly support them against accidental displacement a web 29 is formed vertically across the intake port so that each of the parts of the intake port is controlled by two of the plates 21 which lie in the same horizontal plane. It will be understood that other constructions may be employed for supporting the plates 21 and limiting the amount of opening of the intake port by successive steps to accomplish the same result as above described without departing from my invention.

The crank case 16 has formed through its wall adjacent the lower end of the passageway 20 a port 30 controlled by a rotary valve 31 mounted upon a shaft 32 in a compartment 33 formed in the casing of the engine, which compartment is in communication with the intake manifold 34 which manifold in turn receives its supply of explosive mixture through the pipe 35 containing the throttle valve 28 from a carburetor illustrated diagrammatically at 36. A backing wall 37 extends across the compartment 33 in engagement with the valve 31 to assist in supporting it in proper operative position. The shaft 32 is connected with the shaft 14 by gears 38 and 39 carried respectively by said shafts, the ratio of said gears being 1 to 1, as a result of which the port 30 is opened by the valve 31 for each up stroke of the power piston immediately as the piston begins its upward motion and the port remains open until the upward stroke of the piston is completed so that during this interval the piston may draw into the crank case from the carburetor 36 a quantity of explosive mixture determined by the setting of the throttle valve 28. When the throttle valve is wide open the mixture is drawn into the crank case with a minimum of resistance and as the throttle valve is closed this resistance increases until with the throttle valve in its nearly closed position a relatively small amount of mixture is drawn into the crank case for each upward stroke of the piston.

As is well known in the art, when it is at-

tempted to operate a two-cycle engine on a nearly closed throttle the difficulties above pointed out are encountered and this results directly from the pressure of the mixture 5 in the crank case at that time being too low to send a full charge into the power cylinder. When the amount of this charge delivered to the power cylinder is quite small it is insufficient to displace the gases of 10 combustion of the preceding working stroke while the exhaust port is in its wide open condition, a sufficient amount so that the fresh charge comes into engagement with the spark plug which according to common 15 practice is located in the head end of the cylinder. As a result the engine "misses" and all of the objectionable phenomena referred to above occur. To overcome this, I provide the following construction:

20 At the head end of the power cylinder an extension of the casing is formed and in this extension an auxiliary cylinder 40 is constructed which is preferably parallel with the power cylinder. An auxiliary pis- 25 ton 41 is located in the auxiliary cylinder, this piston being connected by a connecting rod 42 with a crank 43 carried by the shaft 32. The head end of the auxiliary cylinder 40 is in continuous communication with the 30 head end of the power cylinder 10 through a communicating passageway 44 and near the crank end of the auxiliary cylinder an intake port 45 is formed which communicates by a passageway 20 through a check 35 valve 46 with the upper end of the passageway 20. A spark plug 47 is located preferably on the head end of the auxiliary cylinder 40 although it may be located anywhere in the passageway 44 or if preferred, in 40 the head end of the power cylinder 10 adjacent to the opening of the passageway 44. The auxiliary piston 41 is so connected through its crank 43 that it moves practically synchronously with the power piston 45 although I find in practice that it is some- 50 what desirable to have it lag in its operation slightly behind the power piston 11. The displacement effected by the auxiliary piston 41 is preferably so designed that the auxiliary cylinder 40 will be completely 55 filled with fresh mixture for each power stroke even when the engine is running with the throttle valve 28 as nearly closed as possible to still maintain operation of the engine. In other words, for the minimum 60 pressure of mixture in the crank case at the instant the intake ports 17 and 45 are opened by the pistons 11 and 41 respectively, the resultant flow of mixture through 65 the port 45 must be sufficient to fill the auxiliary cylinder 40 and preferably to some- 70 what more than fill it so as to be sure to fill the communicating passageway 44. In this way I provide that the auxiliary cylinder 75 which is really the firing chamber of the en-

gine shall have a charge of fresh mixture in it which extends through the passageway 44 for each working stroke of the engine and since the two pistons operate nearly synchronously the charge in the auxiliary cylinder 70 is compressed at the same time that the gases in the power cylinder are compressed which provides that the dividing line between the fresh mixture introduced into the auxiliary cylinder and the gases in 75 the power cylinder which are at least in part fresh explosive mixture, is maintained practically uniform during the operation of compressing the gases in the cylinders. When therefore the spark is projected across 80 the electrodes of the spark plug 47, this is always done in the presence of a compressed charge of fresh mixture which is at once fired with the result that the ignition is communicated through the passageway 44 to 85 whatever fresh mixture may at the time be compressed in the power cylinder. The resultant pressure produced in the cylinders operates as well upon the auxiliary piston 41 as on the power piston 11 and since the 90 cranks 13 and 43 are at practically the same angular position and are geared together in the ratio of 1 to 1 the pressure developed is effective on the two pistons to run the engine in proportion of the areas of the ends 95 of the pistons. It is to be borne in mind that a two cycle engine running without load requires but little power to drive it, since the amount of mechanism operated by the engine for that condition is practically 100 negligible, whereas with other types of engines in which there are numerous valves and more or less complicated valve gear to be operated the power required to run the engine idle is much greater for the same 105 size engine. This of course accentuates the difficulty met with in operating two cycle engines at no load under ordinary conditions, since the quantity of explosive mixture required for this condition is very 110 small. With my construction, however, it is immaterial how small a charge of mixture is required to operate the engine when running light for as long as the auxiliary cylinder is constructed so as to be entirely filled with 115 fresh mixture for each power stroke of the engine, the fresh mixture compressed in the auxiliary cylinder will be fired at each power stroke and the firing of this mixture will ignite the compressed mixture which 120 may in part constitute the contents of the power cylinder although a considerable quantity of burnt gases from a preceding stroke or strokes may still remain in the power cylinder.

125 It will be observed that the auxiliary piston 41 performs the double function of admitting a charge of fresh mixture to the firing chamber for each power stroke of the engine and also of maintaining practically 130

constant the dividing line between the charge admitted to the auxiliary cylinder and the gases contained in the power cylinder during a compression stroke. While 5 this construction is desirable I do not however limit myself to it, as I may employ other equivalent means for determining the admission of the fresh charge to the firing chamber. When the throttle valve is 10 opened somewhat from the most nearly closed position for which the engine will operate without load a greater quantity of mixture is drawn into the crank case for each compression stroke of the pistons as referred to above, with the result that the 15 pressure on the mixture in the crank case is higher as a result of each power stroke of the engine and that therefore a larger quantity of fresh mixture will flow into the auxiliary cylinder for this condition each time the intake port 45 is opened and that this 20 quantity will increase until the throttle valve 28 is in its wide open position for which condition the maximum quantity of 25 mixture will flow into the auxiliary cylinder for each stroke. In other words, for all conditions except with the throttle valve in its most nearly closed position for which the engine will operate, the amount of fresh 30 mixture delivered to the auxiliary cylinder 40 for each rotation of the shafts 14 and 32, is more than enough to fill the auxiliary cylinder and its passageway 44 which however is no detriment, since the excess is delivered 35 to the power cylinder to form a part of the charge for the next power stroke.

The engine shown in Fig. 1 is provided with a water jacket 48 which operates in a manner well known in the art to prevent the 40 engine from overheating.

As shown in Fig. 4, when my improved engine construction is used in a multi-cylinder arrangement, it lends itself readily to a type of engine desirable for automobile purposes in which the cylinders are cast in one piece. In this construction a four cylinder engine is shown, the intake compartments of the cylinders being indicated at 33 while the auxiliary cylinders are indicated at 40. 45 It will be noted that the auxiliary cylinder may be conveniently located immediately adjacent the end of the intake compartment 33 for each cylinder as a result of which each crank 43 may be well supported by the 50 bearings which in practice are provided for the shaft 32 in the walls of the intake compartments. To facilitate showing in a single view in Fig. 1 the construction of the intake compartment and the auxiliary cylinder, the right hand portion of the figure is 55 broken away so that the part above the break is taken along the line 1^a in Fig. 4 while the part below the break is taken along the line 1 in Fig. 4.

60 In the construction shown in Fig. 5 a simi-

lar arrangement is used, with the exception that the engine is of the double diameter piston type. In this case the power cylinder 10^a is provided with a power piston 11^a which has formed on its lower end a piston 49 of enlarged diameter working in a cylinder 50 of corresponding bore. The cylinder 50 communicates near its upper end with an intake passage 51 in communication with an intake manifold 52 through a puppet valve 75 53. The passage 51 is in communication with an intake passage 54 leading to the cylinder 10^a and the auxiliary cylinder 40^a through a second puppet valve 55. The cylinder 10^a is provided with intake and exhaust ports 17^a and 18^a respectively and the auxiliary cylinder is provided with an auxiliary piston 41^a of substantially the same construction as shown and described in connection with Fig. 1, the only difference being that the initial compression of the mixture is accomplished by means of the piston 49 instead of in the crank case 16 as shown in Fig. 1. It is immaterial which form of initial compression is used although the two 90 diameter piston construction is somewhat more expensive to build and the crank case compression type of engine is entirely satisfactory in operation when well made.

As a result of the improved construction 95 above described it will be observed that I have entirely eliminated missing of the engine when running idle and that therefore the vibration resulting heretofore from an accumulation of excessive charges with an 100 occasional firing of a heavy charge is eliminated and that it is immaterial with my construction whether the engine scavenges perfectly when running without load, since the 105 fresh mixture required for each working stroke is fired whether all of the burnt gases of the preceding stroke are discharged from the cylinder or not. It will be observed that it is impossible with my construction for the auxiliary cylinder to contain any burnt 110 gases after compression for any condition of operation and as long as this takes place it is immaterial whether the power cylinder scavenges or not for conditions of light running. It is well known that carburetors 115 of modern construction are so designed that the mixture delivered to the engine for a nearly closed throttle condition is richer than delivered by the same carburetor if properly adjusted for full load condition of 120 the throttle valve, which makes it more certain that firing will occur for each working stroke with my improved construction for any condition of the throttle valve for which the engine will operate. Again, it 125 will be evident that since firing occurs for each working stroke it is impossible for the engine to become so loaded with rich mixture that it will not operate. Backfiring with two cycle engines operating under 130

light load has usually been due to delaying the spark by such an amount in an attempt to make the engine fire properly on light load that an insufficient time interval is allowed for the charge to burn before the intake port is opened, as a result of which when the intake port is opened the fresh mixture in the compression chamber is ignited. Proper operating conditions require that the spark shall be so adjusted that a sufficient time interval is afforded in which to burn the charge in the power cylinder before the intake port is opened and since my improved construction secures uniform firing, the spark may be left in its proper position of adjustment for full load operation even when the engine is running under no load, with the result that an ample time interval is afforded for all practical conditions even with the ordinary construction of intake port. My improved intake port construction, however, entirely eliminates all possibility of backfiring since it is well known that backfiring cannot occur if the velocity of the gas flow through the port is sufficiently high. By my construction I may make the velocity of the mixture flowing into the power cylinder as high as desired by subdivision of the port by means of the plates 21, since by so doing the effective area of the intake port is graded in a succession of steps from a cross section sufficient to produce a high velocity of flow into the power cylinder for the minimum charge of fresh mixture for no load condition to full opening of the port for the largest quantity of fresh mixture required to flow through the port on full load condition. The check valve 46 is provided so that the passageway 20^a may remain filled with fresh mixture at all times, so that the auxiliary cylinder will certainly receive a sufficient charge of fresh mixture even for extreme conditions of light running of the engine although for ordinary operating conditions I find it is unnecessary to employ said check valve.

It will be understood that my invention is not limited to any specific combustible for operating my improved engine, nor is it limited to any particular manner of introducing the combustible into the cylinder or any particular manner of firing it. Any combustible and method of introducing the same and firing it known to the art in connection with internal combustion engines may be employed, the particular construction and operation described above in this connection being merely one operative embodiment to illustrate the application of my invention to an internal combustion engine. My invention in its broad aspect consists in providing the power cylinder of an internal combustion engine with an auxiliary firing chamber of such volume that the mini-

mum amount of combustible required for a power stroke of the engine when running without load, shall, by its introduction by suitable means into the firing chamber, be brought in contact with the firing devices associated with the firing chamber, to the end that the combustible shall be fired with certainty for each power stroke of the engine for the slowest speed at which the engine can be made to run without load, in view of the friction and inertia of the moving parts. Furthermore, if desired, while I have shown the power cylinder and firing chamber supplied with combustible from the same source and simultaneously controlled as to fuel supply, I may employ independent means for supplying the firing chamber with fuel and controlling the quantity supplied, from the means employed to supply and control the fuel delivered to the power cylinder. 85

For some purposes the intake port valve 22 may be completely closed when the throttle valve 28 is in its nearly closed condition, as a result of which all of the pressure in the compression chamber is available to 90 force the relatively small charges into the firing chamber, thus effectively and positively filling the firing chamber for each power stroke. If desired, the rod 25 may be disconnected from the crank 24 and the valve 95 22 may be independently operated, as for example on stationary engines or boat engines where the periods of idle running are infrequent.

While I have shown my invention in the 100 particular embodiments above described, it will be understood that I do not limit myself to these constructions, as I may employ any equivalents thereof known to the art at the time of the filing of this application 105 without departing from the scope of the appended claims.

What I claim is:

1. In a two cycle engine, the combination of a power cylinder having intake and exhaust ports near its crank end, a power piston in said cylinder controlling the opening and closing of said ports, a compression chamber for containing explosive mixture under pressure, an auxiliary firing cylinder having at its head end an open passageway connecting with the head end of the power cylinder, an intake passageway from said compression chamber to said intake port and to the crank end of said auxiliary cylinder, an auxiliary piston in said auxiliary cylinder for opening said intake passageway to the auxiliary cylinder during intake, and devices for firing the mixture in said auxiliary cylinder, said firing chamber being of a volume substantially filled with explosive mixture from said intake passageway for each cycle of the engine when running without load. 120

2. In a two cycle engine, the combination 130

- of a power cylinder having intake and exhaust ports near its crank end, a power piston in said cylinder controlling the opening and closing of said ports, a compression chamber for containing explosive mixture under pressure, an auxiliary firing cylinder having at its head end an open passageway connecting with the head end of the power cylinder, an intake passageway from 5 said compression chamber to said intake port and to the crank end of said auxiliary cylinder, an auxiliary piston in said auxiliary cylinder for opening said intake passageway to the auxiliary cylinder during intake, and devices for firing the mixture in 10 said auxiliary cylinder, said firing chamber being of a volume substantially filled with explosive mixture from said intake passageway for each cycle of the engine when running without load, a crank shaft connected 15 with the power piston, and equal ratio gearing connecting said shaft and said auxiliary piston.
3. In a two cycle engine, the combination 20 of a power cylinder having intake and exhaust ports near its crank end, a power piston in said cylinder controlling the opening and closing of said ports, a compression chamber for containing explosive mixture 25 under pressure, an auxiliary firing cylinder having at its head end an open passageway connecting with the head end of the power cylinder, an intake passageway from said compression chamber to said intake port 30 and to the crank end of said auxiliary cylinder, an auxiliary piston in said auxiliary cylinder for opening said intake passageway to the auxiliary cylinder during intake, devices for firing the mixture in 35 said auxiliary cylinder, said firing chamber being of a volume substantially filled with explosive mixture from said intake passageway for each cycle of the engine when running without load, a crank shaft connected 40 with the power piston, equal ratio gearing connecting said shaft and said auxiliary piston, and a valve for closing or opening said intake port as the engine is throttled or freely supplied 45 with explosive mixture.
4. In a two cycle engine, the combination 50 of a power cylinder having intake and exhaust ports near its crank end, a power piston in said cylinder controlling the opening and closing of said ports, a compression chamber for containing explosive mixture under pressure, a firing chamber connected 55 with the head end of the power cylinder by an open passageway, an intake passageway from said compression chamber to said intake port and to said firing chamber, a valve for opening said intake passageway to the firing chamber during intake, devices for 60 firing the mixture in said firing chamber, said firing chamber being of a volume substantially filled with explosive mixture from said intake passageway for each cycle of the engine when running without load, a valve actuated with the engine throttle valve for closing or opening said intake port as the engine is throttled or freely supplied 65 with explosive mixture, and transverse partitions in said intake port engaging said valve for changing the effective cross section of said intake port.
5. In a two cycle engine, the combination 70 of a power cylinder having intake and exhaust ports near its crank end, a power piston in said cylinder controlling the opening and closing of said ports, a throttle valve for supplying said compression chamber with mixture, a valve for closing or opening said intake port as the engine is throttled or freely supplied 75 with explosive mixture, operating connections between said last named valve and said throttle valve, and transverse partitions in said intake port engaging said valve for changing the effective cross section of said intake port.
6. In a two cycle engine, the combination 80 of a power cylinder having intake and exhaust ports near its crank end, a power piston in said cylinder controlling the opening and closing of said ports, a compression chamber for containing explosive mixture under pressure, a firing chamber connected 85 with the head end of the power cylinder by an open passageway, an intake passageway from said compression chamber to said intake port and to said firing chamber, a valve for opening said intake passageway to the 90 firing chamber during intake, devices for firing the mixture in said firing chamber, a valve actuated with the engine throttle valve for closing or opening said intake port as the engine is throttled or freely supplied 95 with explosive mixture, and transverse partitions in said intake port engaging said valve for changing the effective cross section of said intake port.
7. In a two cycle engine, the combination 100 of a power cylinder having intake and exhaust ports near its crank end, a power piston in said cylinder controlling the opening and closing of said ports, a throttle valve for said engine for controlling the supply of 105 combustible mixture thereto, a compression chamber for containing explosive mixture under pressure by the operation of said power piston, a firing chamber connected with the head end of the power cylinder by 110 an open passageway, an intake passageway from said compression chamber to said intake port and to said firing chamber, a valve for opening said intake passageway to the firing chamber during intake, devices for 115 firing the mixture in said firing chamber, said firing chamber being of a volume substantially filled with explosive mixture from said intake passageway for each cycle of the engine when running without load, a valve actuated with the engine throttle valve for closing or opening said intake port as the engine is throttled or freely supplied 120 with explosive mixture, and transverse partitions in said intake port engaging said 125 valve for changing the effective cross section of said intake port.
8. In a two cycle engine, the combination 130 of a power cylinder having intake and exhaust ports near its crank end, a power

piston in said cylinder controlling the opening and closing of said ports, a throttle valve for said engine for controlling the supply of combustible mixture thereto, a compression chamber for containing explosive mixture under pressure by the operation of said power piston, a firing chamber connected with the head end of the power cylinder by an open passageway, an intake passageway 5 from said compression chamber to said intake port and to said firing chamber, a valve for opening said intake passageway to the firing chamber during intake, devices for firing the mixture in said firing chamber, 10 a valve actuated with the engine throttle valve for closing or opening said intake port as the engine is throttled or freely supplied with explosive mixture, and transverse partitions in said intake port engaging said 15 valve for changing the effective cross section of said intake port.

8. In a two cycle engine, the combination of a power cylinder having intake and exhaust ports near its crank end, a power piston in said cylinder controlling the opening and closing of said ports, a compression chamber for containing explosive mixture under pressure, an auxiliary firing cylinder having at its head end an open passageway 20 connecting with the head end of the power cylinder, an intake passageway from said compression chamber to said intake port and to the crank end of said auxiliary cylinder, an auxiliary piston in said auxiliary cylinder for opening said intake passageway to the auxiliary cylinder during intake, devices for firing the mixture in said auxiliary cylinder, said firing chamber being of a volume substantially filled with explosive mixture 25 30 35 40 45 50

ture from said intake passageway for each cycle of the engine when running without load, a crank shaft connected with the power piston, equal ratio gearing connecting said shaft and said auxiliary piston, a valve for closing or opening said intake port as the engine is throttled or freely supplied with explosive mixture, and transverse partitions in said intake port engaging said valve for changing the effective cross section of said intake port.

9. In a two cycle engine, the combination of a power cylinder having an exhaust port, a power piston in said cylinder controlling the opening and closing of said port, an auxiliary cylinder in open communication with said power cylinder and having an intake port, an auxiliary piston in said auxiliary cylinder for controlling the opening and closing of said intake port, and means for 55 60 65 70 75 80 85 90 95 100 105 110 115 120 125

firing the mixture in said auxiliary cylinder, said auxiliary cylinder being of a volume to be filled with explosive mixture for each cycle of the engine when the engine is running at slow speed without load, each of

said pistons making one out-stroke and one 65 in-stroke for a complete cycle of operation of the engine.

10. In a two cycle engine, the combination of a power cylinder having an exhaust port, a power piston in said cylinder controlling 70 the opening and closing of said port, an auxiliary cylinder in open communication with said power cylinder and having an intake port, an auxiliary piston in said auxiliary cylinder for controlling the opening and 75 closing of said intake port, means for firing the mixture in said auxiliary cylinder, said auxiliary cylinder being of a volume much smaller than the volume of said power cylinder to be filled with explosive mixture for 80 each cycle of the engine when the engine is running at slow speed without load, a crank shaft, a connecting rod extending from said power piston to said shaft, and gearing connecting said auxiliary piston with said shaft 85 in the ratio of one to one.

11. In a two cycle engine, the combination of a power cylinder having an exhaust port, a power piston in said cylinder controlling the opening and closing of said port, an auxiliary cylinder in open communication with said power cylinder and having an intake port, an auxiliary piston in said auxiliary cylinder for controlling the opening and 90 closing of said intake port, means for firing the mixture in said auxiliary cylinder, said auxiliary cylinder being of a volume much smaller than the volume of said power cylinder to be filled with explosive mixture for 95 each cycle of the engine when the engine is running without load, an intake passageway communicating with said intake port, and a check valve in said intake passageway.

12. In a two cycle engine, the combination of a power cylinder, a power piston in said 105 cylinder, a crank shaft connected with said power piston, an auxiliary cylinder communicating with said power cylinder, an auxiliary piston in said auxiliary cylinder, an auxiliary crank shaft connected with said 110 auxiliary piston, a compression chamber, a rotary valve for controlling admission to said compression chamber and gearing connecting said crank shafts and valve in the ratio of one to one, said rotary valve being 115 mounted upon and driven by said auxiliary crank shaft.

13. In a two cycle engine, the combination of a power cylinder having intake and exhaust ports for fuel mixture and spent gases 120 respectively, a power piston in said cylinder controlling the opening and closing of said ports, an auxiliary cylinder of small volume compared with the volume of the power cylinder in open but restricted communication 125 with the head end of the power cylinder, an auxiliary piston in said auxiliary cylinder, and means for supplying said auxiliary cyl-

inder with a minimum firing charge for no load running filling said auxiliary cylinder for each cycle of the engine, said minimum charge being much smaller than the volume of the power cylinder.

14. In a two cycle engine, the combination of a power cylinder having intake and exhaust ports for fuel mixture and spent gases respectively, a power piston in said cylinder controlling the opening and closing of said ports, an auxiliary cylinder of small volume compared with the volume of the power cylinder in open but restricted communication with the head end of the power cylinder, an auxiliary piston in said auxiliary cylinder, means for supplying said auxiliary cylinder with a minimum firing charge for no load running filling said auxiliary cylinder for each cycle of the engine, said minimum charge being much smaller than the volume of the power cylinder, and means in the auxiliary cylinder for firing the charge therein.

15. In a two cycle engine, the combination of a power cylinder having intake and exhaust ports for fuel mixture and spent gases respectively, a power piston in said cylinder controlling the opening and closing of said ports, an auxiliary cylinder of small volume compared with the volume of the power cylinder in open but restricted communication with the head end of the power cylinder, an auxiliary piston in said auxiliary cylinder, means for supplying said auxiliary cylinder with a minimum firing charge for no load running filling said auxiliary cylinder for each cycle of the engine, said minimum charge being much smaller than the volume of the power cylinder, and gearing connecting said pistons in the ratio of one to one.

16. In a two cycle engine, the combination of a power cylinder having intake and exhaust ports for fuel mixture and spent gases respectively, a power piston in said cylinder controlling the opening and closing of said ports, an auxiliary cylinder of small volume compared with the volume of the power cylinder in open but restricted communication with the head end of the power cylinder, an auxiliary piston in said auxiliary cylinder, means for supplying said auxiliary cylinder with a minimum firing charge for no load running filling said auxiliary cylinder for each cycle of the engine, said minimum charge being much smaller than the volume of the power cylinder, a throttle valve for the engine, and a valve for closing said intake port as said throttle valve is closed.

17. In an engine, the combination of a power cylinder having an intake port, a power piston in said cylinder, a throttle valve for controlling the supply of mixture to said cylinder, a control valve for opening

or closing said intake port, and devices connecting said throttle valve and said control valve to either open or close both said valves by the same operation.

18. In an engine, the combination of a power cylinder having an intake port, a power piston in said cylinder, a throttle valve for controlling the supply of mixture to said cylinder, a control valve for opening or closing said intake port, devices connecting said throttle valve and said control valve to open or close both said valves by the same operation, and transverse partitions in said intake port for changing the effective cross-section of said intake port by operation of said control valve.

19. In an engine, the combination of a power cylinder, a power piston in said cylinder, said cylinder having an exhaust port and an intake port for compressed mixture at its crank end opened and closed by said piston, a firing chamber in communication with the head end of said cylinder, a port supplying said chamber with compressed mixture, a positively actuated valve for opening and closing said last named port, and means in said firing chamber for firing the mixture therein, said chamber being of small volume filled with mixture for the smallest charge of mixture for which the engine will run on no load.

20. In an engine, the combination of a power cylinder, a power piston in said cylinder, said cylinder having an exhaust port and an intake port for compressed mixture at its crank end opened and closed by said piston, a firing chamber in communication with the head end of said cylinder, a port supplying said chamber with compressed mixture, a positively actuated valve for opening and closing said last named port, and means in said firing chamber for firing the mixture therein, said chamber being of small volume filled with mixture for the smallest charge of mixture for which the engine will run on no load, the communication between said cylinder and chamber being by an open passageway of smaller cross section than the cross section of said chamber.

21. In an engine, the combination of a power cylinder, a power piston in said cylinder, said cylinder having an exhaust port and an intake port for compressed mixture at its crank end opened and closed by said piston, a firing chamber in communication with the head end of said cylinder, a port supplying said chamber with compressed mixture, a positively actuated valve for opening and closing said last named port, means in said firing chamber for firing the mixture therein, said chamber being of small volume filled with mixture for the smallest charge of mixture for which the

- engine will run on no load, a throttle valve for controlling the supply of mixture to the engine, a control valve for changing the size of the intake port of the power cylinder, 5 and connections between said throttle valve and said control valve for moving said control valve toward its closed position when said throttle valve is moved to its position producing slow speed of the engine.
- 10 22. In an engine, the combination of a power cylinder, a power piston in said cylinder, said cylinder having an exhaust port and an intake port for compressed mixture at its crank end opened and closed by said 15 piston, a firing chamber in communication with the head end of said cylinder, a port supplying said chamber with compressed mixture, a positively actuated valve for opening and closing said last named port. 20 means in said firing chamber for firing the mixture therein, and a throttle valve for decreasing the mixture supplied to the engine to secure slow speed with no load, said

chamber being of a volume filled with mixture for the slowest speed no-load condition 25 of the throttle valve.

23. In an engine, the combination of a power cylinder, a power piston in said cylinder, said cylinder having an exhaust port and an intake port for compressed mixture 30 at its crank end opened and closed by said piston, a firing chamber in communication with the head end of said cylinder, a port supplying said chamber with compressed mixture, a positively actuated valve for 35 opening and closing said last named port, and means in said firing chamber for firing the mixture therein, said chamber being of small volume filled with mixture for the smallest charge of mixture for which the 40 engine will run on no load, said firing chamber extending laterally from one side of the head end of said cylinder.

In witness whereof I hereunto subscribe my name this 21st day of May, A. D. 1917. 45

CHARLES L. BOWDEN.
